[57] CLAIM

The ornamental design for a condensed multiple convergence reflective linear optical and receiver plate for solar conversion or the like, substantially as shown and described.

DESCRIPTION

FIG. 1 is a perspective view of a condensed multiple convergence reflective linear optical and receiver plate for solar conversion or the like, showing my new design. FIG. 2 is a perspective view of a second embodiment of my new design.

The underside of each embodiment is plain. The plate of each embodiment is understood to have indeterminate length.
